UNITED STATES PATENT OFFICE.

WESLEY MACK HAMILTON, OF TAMPA, FLORIDA.

WATER-HEATING ATTACHMENT.

*1,333,110.

Specification of Letters Patent. Patented Mar. 9, 1920.

Application filed June 9, 1919. Serial No. 302,949.

To all whom it may concern:

Be it known that I, WESLEY M. HAMILTON, a citizen of the United States, residing at Tampa, in the county of Hillsborough 5 and State of Florida, have invented certain new and useful Improvements in Water-Heating Attachments, of which the following is a specification.

This invention relates to stove attachments, particularly to water heating attachments for gaseous or liquid fuel burner stoves, and has for its object the provision of a water heating device comprising a ring member formed of piping and disposed 10 above and outwardly of each burner of the stove, a pipe coil member of larger diameter disposed within the grid opening above each burner and arranged above and outwardly of the ring pipe, and a plurality of relatively small tubes connecting the ring pipe and the upper pipe whereby water fed to the ring pipe will be very quickly heated during its flow therethrough and through 15 said tubes, the uppermost pipe member being connected with pipes leading to a storage tank, from the bottom of which extends a pipe feeding the lower or ring members.

An important object is the provision of a device of this character in which the feed 20 ring, pipe coil and the connecting tubes therebetween are arranged in such position that the flame from the burner will play fully against them while these various members will not in any way interfere with the 25 action of the flame when the stove is used for cooking so that the water heating function may be conveniently carried out without in any way detracting from the utility of the stove during cooking operations.

Another object is the provision of an attachment of this character which may be placed upon existing stoves of ordinary construction, the pipe members being arranged 30 within the grid openings and a further 35 feature is that the grids serve as protecting means for preventing injury to the pipes and their connecting tubes.

An additional object is the provision of a device of this character which will be 40 simple and inexpensive in manufacture, highly efficient in use, durable in service, and a general improvement in the art.

With the above and other objects and advantages in view, the invention consists in 45 the details of construction to be hereinafter more fully described and claimed, and illus-

trated in the accompanying drawings, in which—

Figure 1 is a side elevation of a stove having my attachment associated therewith and showing a water tank, 60

Fig. 2 is a plan view of the stove with the attachment in place,

Fig. 3 is a cross sectional view, and

Fig. 4 is a detail sectional view. 65

Referring more particularly to the drawings, the letter A designates a stove of the type having liquid or gaseous burners B disposed beneath grid openings C and D, the grid openings C having disposed therein grids E and the openings D having disposed therein plates F, each having a central opening G disposed immediately above the burner B. The letter H designates a water tank, 70 75

In carrying out my invention I provide at the central part of the stove beneath the plane of the burners, a coupling 10 into the bottom of which leads a water feed pipe 11 leading from the lower portion of the 80 tank H. Extending in an upwardly inclined direction from each arm of the coupling 10, is a pipe 12 which may be formed in sections connected by the usual unions 13.

Disposed above each burner B is a ring 85 member 14 formed of piping and to which is connected one of the pipes 12. An almost circular coil pipe 15 is disposed within each of the grid openings and is disposed above the pipe ring 14. The diameter of 90 the ring 14 is greater than the diameter of the burner B so that the ring will be disposed outwardly therebeyond and the diameter of the pipe coil 15 is greater than the diameter of the ring 14. The ring pipe 95 14 communicates with the coil pipe 15 by means of a plurality of tubes 16 of relatively small diameter which extend upwardly in an inclined direction inwardly of the ring member 14 for a portion of their 100 lengths, which then extend vertically upwardly and then slightly upwardly and outwardly to the coil pipe 15.

One end of each pipe coil 15 is closed, as shown at 17, and the other extends along 105 and above the top of the stove, as shown at 18, and has connected therewith a discharge pipe 19, a suitable union 20 being employed. These pipes 19 extend upwardly in a slightly inclined direction and are connected at their 110 other ends by suitable couplings 21 with the lower ends of abruptly ascending pipes

22 which are connected at their upper ends by a common member 23 from which extends a pipe 24 discharging into the top of the tank.

5 In order that the attachment may be properly supported within the grid openings C, the grids E are provided at their corners with relatively long inwardly extending arms 25 which are adapted for engagement

10 thereon of the pipe coil 15. The coils 15 in these grid openings C are obviously inserted from the top and will be supported so as to prevent displacement. The arrangement is such that the coils 15 will be disposed either 15 flush with or below the top surfaces of the grids whereby to prevent injury to any of the pipes or tubes.

In order that the coils 15 may be supported within the grid openings D, the 20 plates F closing these openings D carry on their undersides brackets 28 which are detachably connected by means of suitable screws 29 or the like and which extend inwardly beneath the coils 15. It will be obvious that the coils 15 will be inserted in 25 place from the underside of the plates F and these plates F will cover the coils 15 as well as the tubes 16 and prevent damage.

When the device is in use it will be seen 30 that water will flow from the tank H, through the pipe 11, coupling 10, pipes 12, ring members 14, tubes 16, coils 15, pipes 18 and 19, pipes 22, and into the pipe 24 whence it will flow into the tank H. 35 It will be observed that the flame from the burners will play against the tubes 16 and the coil pipes 15 and very quickly and easily heat the water while at the same time these various pipes and tubes will not stop the direction of the flame or interfere with it in any 40 way in the use of the stove for cooking purposes.

While I have shown and described the preferred embodiment of my invention, it 45 is of course to be understood that I reserve the right to make such changes in the form, construction, and arrangement of parts as will not depart from the spirit of the invention or the scope of the subjoined claims.

50 I claim:

1. A water heating attachment for stoves having liquid or gaseous fuel burners, comprising a ring member disposed above and

outwardly of each burner, a common feed pipe extending below all of the burners and 55 having branch pipes extending upwardly and connected with said ring members, a pipe coil disposed above and outwardly beyond each ring member, a plurality of tubes, connected with each ring member and the 60 coil pipe thereabove, and a discharge pipe connected with each of said coil pipes.

2. A water heating attachment for gaseous and liquid fuel burner stoves comprising a ring member disposed above and outwardly of each burner, a common feed pipe disposed below the burners and having branch pipes connected with said ring members, a coil pipe disposed above and outwardly of each ring member, a plurality of 70 tubes of relatively small diameter communicating with each ring member and extending upwardly with respect thereto and having their upper ends extending outwardly and connected with said pipe coil, 75 one end of each pipe coil being closed and the other end thereof being connected with a discharge pipe.

3. In combination with a water tank and a stove having liquid or gaseous fuel burners, a feed pipe extending from the lower portion of said tank and disposed below the plane of said burners, a coupling member on the end of said feed pipe, a plurality of branch pipes leading from said coupling 85 member and extending in an upwardly inclined direction, a ring pipe member disposed above and outwardly of each burner, said branch pipes being connected with said ring pipes, a coil pipe disposed above and 90 outwardly of each ring pipe member, a plurality of tubes of relatively small diameter connecting said ring pipes and said coil pipes, one end of each coil pipe being closed, a discharge pipe connected with the other 95 end of each coil pipe and extending in an upwardly inclined direction toward the top of said pipe, a common connection connected with the upper ends of all of said discharge pipes, and a pipe connected with said common connection and communicating with the top of said tank.

In testimony whereof I hereto affix my signature.

WESLEY MACK HAMILTON.
